COLLAR AND LIKE GARMENT PARTS

Benjamin Liebowitz, Lewisboro, N. Y., assignor
to Trubenzing Process Corporation, New York,
N. Y., a corporation of New York

Application July 21, 1950, Serial No. 175,269

21 Claims. (Cl. 2—131)

1

This invention relates to collars and like garment parts. It relates particularly to collars for men's and boys' shirts; and is a continuation-in-part of inventions disclosed in my application Serial No. 79,757, filed March 5, 1949 (now abandoned), and in my application Serial No. 153,050, filed March 31, 1950.

As such collars are conventionally produced today, they almost invariably consist of two parts, viz., collar-top or cape portion and the collarband portion, each of which comprises three plies of fabric. Where these two parts are joined along the collarbanding seam there are nine plies of fabric which require fairly heavy tensions in sewing. The result is a structure which not merely tends to shrink unduly but also to shrink unpredictably. Thus, for example, there is usually a very substantial difference between such collars when hand-laundered on the one hand, and when commercially laundered on the other. This difficulty can be overcome by cutting the cape and band portions in one piece instead of in two pieces. This, however, introduces two problems. One is the greater difficulty of manufacture, and the second is the problem of determining the foldline (collars for so-called sport shirts are not included in this discussion; they are usually made one-piece but large manufacturing tolerances are permitted and moreover they do not demand a predetermined foldline).

This invention concerns the latter, i. e., the matter of the foldline, with particular reference to so-called fused collars.

Such collars usually are made of three plies which will be called herein the face ply, the lining ply and the back ply. The lining ply bears the adhesive material in the form of yarns soluble in certain organic solvents or in the form of a coating. To form a foldline in such fused collars, it has heretofore been proposed to place a resist or alternatively a thin strip of tissue on the side of the lining facing the back ply, along a narrow zone which will prevent adhesion between the back ply and the lining along that zone, thereby creating a zone of greater flexibility than the rest of the collar, along which the collar will naturally fold because of that greater flexibility, all as disclosed in my Patent No. 2,118,407. This invention relates to a foldline produced in that manner, i. e., by means of a resist or tissue, and has for its object ease of manufacture and the production of an improved foldline, and has other objectives that will hereinafter appear.

When a foldline is produced merely by means of resist or tissue, as in Patent No. 2,118,407, the collar may be more flimsy than is desired. To

2

overcome this, extra stiffening in the band portion adjacent the foldline is highly desirable. Furthermore, a foldline produced by resist or tissue alone tends to hug the neck too closely with the result that it soils more readily than in the case of conventional collars. I overcome this tendency at least to a substantial degree not only by the extra stiffening in the band but also by so producing the foldline that it has something of

10 a roll.

When a resist or tissue is applied directly onto an adhesive-bearing lining fabric cut to the shape of a collar ply, as disclosed in Patent No. 2,118,407, there is considerable loss of production time not only because of the method by which the resist or tissue must be applied in order to be accurately located, but also because of the drying time necessary for such application. One of the primary objects of this invention is to overcome this production delay by applying the resist or weaving the tissue along one edge of a tape, which in turn is subsequently located with desired precision on the lining ply. Where resist is used it can be applied to a tape in a continuous manner by passing the edge of the tape continuously over a roll or between rolls wetted with the resist material; drying can be done also more or less automatically by passing the tape through a drying oven before it emerges into the atmosphere. Or instead of resist a thin tissue can be incorporated 20 in the tape in the weaving process. In any event, the operation of applying resist or integrally weaving a tissue along an edge of a tape is very fast compared with applying the resist along an accurately located predetermined zone on a lining. By methods described in my application Serial No. 79,758, filed March 5, 1949, for "Method and Apparatus for Making Collars or the Like," I have shown how the tape can be applied to the lining in a very rapid and highly accurate manner. All told, then, the use of a tape with resist applied or tissue woven along one edge provides 30 not only a better collar but a collar which can be produced more speedily and hence more economically.

40 The tissue referred to in Patent No. 2,118,407 is there described as made of cellophane or similar thin material whereas in this present invention I use a woven tissue which is preferably integrally woven in a tape. In this connection, when a woven tissue is thus used for the purpose here intended, its weave preferably is substantially more flexible than the fabric of the back 50 ply of the collar so that the foldline zone not only shall be more flexible than the collarband but also more flexible than the portion of the

55

collartop adjacent to the foldline zone in the case of that embodiment of my invention wherein the tissue that is integrally woven with the tape is used without added resist to prevent its adhesion to the collar lining. I have found that a woven tissue can be produced sufficiently thin and flexible for the purposes here intended by using fewer and lighter warp yarn in said tissue zone, and in particular by using rayon warp yarn, e. g., Bemberg, in said zone. With properly selected warp yarns and spacing thereof in said tissue zone, the weft yarns can be the same as in the body portion of the tape without unduly impairing the flexibility of said tissue zone. In such case the tissue zone can be readily woven integrally with the body portion of said tape. On the other hand, the tissue portion can be woven separately with lighter weft yarns and subsequently attached to the body portion of the tape, e. g. by stitching, but this procedure is much less convenient and economical than weaving both portions of the tape integrally with each other.

The net effect of using the foldline-forming means of this invention is to produce a softening effect on the foldline zone of the collar and a stiffening effect on the collarband in the zone adjacent the foldline zone. It is a characteristic of this invention that these dual effects are achieved by unitary means independent of the lining.

This invention will be better understood by reference to the drawings in which,

Fig. 1 is a plan view of a one-piece collar embodying one form of this invention, with the collar unfolded and with a portion of the face ply and the lining ply broken away;

Fig. 2 is a cross-section on the line 2—2 of Fig. 1;

Fig. 3 is the same as Fig. 2 but with the collar folded down;

Fig. 4 is a diagrammatic showing of a tape which may be employed in the practice of my invention to form the foldline and to put extra stiffness in the band;

Fig. 5 is a cross-section on the line 5—5 of Fig. 4;

Fig. 6 is a cross-section of a modified tape;

Fig. 7 is a cross-section of a strip cut from a larger piece to serve the purpose of the tape;

Fig. 8 is a cross-section of another form of strip cut from a large piece;

Figs. 9, 10 and 11 are cross-sections of alternative tape constructions similar to Fig. 8 but omitting certain of the elements thereof as shown in Fig. 8;

Fig. 12 is a fragmentary section similar to the central portion of Fig. 2 showing the collar plies in combination with the fabric strips shown in Figs. 7, 8 and 9;

Fig. 13 is a fragmentary section similar to the upper portion of Fig. 3 when the combination shown in Fig. 12 is employed;

Fig. 14 is a diagrammatic showing of a modified tape which employs a more flexible fabric construction in the foldline zone;

Fig. 15 is a cross-section on the line 15—15 of Fig. 14;

Fig. 16 is a cross-section similar to Fig. 3 but comprising the tape shown in Figs. 14 and 15; and

Fig. 17 is a cross-section showing the strip of Fig. 15 when employed with resist material along the edge portion thereof.

It will be understood that the drawings are 75

purely diagrammatic and that certain dimensions are grossly exaggerated for purposes of clarity, and are not to be construed as indicating the number of yarns employed, etc. Referring to the drawings, 11 is the collartop portion and 12 is the collarband portion of the one-piece collar as shown attached to a shirt 13. As seen in FIG. 2 the collar 11—12 comprises three plies, viz., a face ply 14, a lining ply 15 and a back ply 16. The lining ply 15 contains an adhesive material either in the form of yarns or coating. The collar is shown as made according to usual running and turning procedures in which the running stitch is shown at 17 and the external stitch at 18. The collar plies are shown attached to the shirt 13 in a conventional manner, i. e., by stitching 19 and 20. If conventional practices were followed in making the collar, unduly large variations would result in collar dimensions and in the location of the foldline. In my aforesaid application, Serial No. 79,758 I have disclosed new techniques for manufacturing such collars whereby these unduly large variations are eliminated.

A characteristic feature of the form of my invention shown in Figs. 1 to 3 is the use of a strip of fabric 10 which has an edge portion 10a such that the main body of the strip 10 is fused to the lining and also preferably to the back ply 16, whereas the edge portion 10a is fused neither to the lining 15 nor the back ply 16. The unfused zone on each side of the edge portion 10a results in having only two fused plies in said zone, viz., the face ply 14 and the lining ply 15. This zone will therefore be a zone of greater flexibility than the rest of the collar along which the collar will automatically fold after laundering. The unfused zone along the edge 10a is indicated in FIG. 1 by the reference character 10z and it is this zone which is occupied by the selvage or edge portion 10a of the strip 10 shown in Figs. 2, 3, 12 and 13 and likewise in Figs. 4, 6, 7, 8, 9, 10, 11, 15, 16 and 17. In FIG. 1 a portion of the face ply 14 and of the lining ply 15 has been broken away and where this has been done the stippling indicates the adhesive by which the lining ply 15 is fused both to the back ply 16 and to the strip 10 except along the edge portion 10a where the resist 9 is applied. Of course, the lining ply 15 may also be fused to the face ply 14, and preferably the strip 10 is fused to the back ply except along the edge portion 10a.

When resist is employed, as in Figs. 1, 2 and 3, the strip 10 may take any of several possible forms and may be made up either as a tape or may be cut from a larger piece as a tape-like strip. If desired the edge portion 10a of the strip 10 may be of increased thickness, as by the employment of a cord or the equivalent along this edge. One form of strip wherein the edge portion 10a is of increased thickness is illustrated in Figs. 4 and 5.

In these figures 21 represents a corded edge; 22 represents ordinary warp cotton yarns; 23 represents an ordinary cotton filler, and 24 represents yarns of cellulose derivative. In practice, the entire width of such tape may conveniently be made about $\frac{3}{8}$ of an inch, the total number of ends of cotton may be, for instance, 24, and the total number of ends of cellulose derivative yarns may be 12, i. e., 2 cotton warp yarns to each cellulose derivative warp yarn. To prevent fusion of the tape to the adhesive-bearing lining in the collar in order to form the zone 10z, the region of the tape in the neighborhood of

the cord 21 constituting the edge portion 10a is coated with a resist material, shown at 9.

Instead of using the cord as indicated at 21 in Figs. 4 and 5 I may use a plain selvage edge without adhesive yarns as shown in Fig. 6, which is a cross-section corresponding to Fig. 5 but substitutes the ordinary cotton yarns 22 for the cord 21. The resist is placed over the cotton yarns in the region of the edge portion 10a as indicated at 9 in Fig. 6. In Figs. 2 and 3 the strip 10 is shown for purposes of illustration as being of the type indicated in Fig. 6, although when the strip shown in Figs. 4 and 5 is used in combination with the collar plies the showing thereof on the smaller scale of Figs. 2 and 3 is essentially the same as that of Figs. 2 and 3.

While a tape specially woven for the purpose affords a very convenient means for making the foldline according to this invention, it is not necessary to use a specially woven tape. Fig. 7 shows a cross-section through a strip of lining material such as is customarily used in the manufacture of fused collars, i. e., a strip containing cellulose derivative yarns as indicated at 24 as well as the cotton yarns 22 and filler 23. This strip is cut from such yard goods to appropriate width and the edge portion 10a is treated with resist as shown at 9a on one side and at 9b on the opposite side. On account of the presence of cellulose derivative yarns in the edge of such a strip, it is very desirable to treat both sides of the edge with the resist as shown. If only one side were treated fusion would take place between the back ply and the strip in the folding zone and this would tend to stiffen said folding zone.

Fig. 8 is a cross-section of a so-called coated fabric used in the manufacture of fused collars in which an ordinary fabric is shown at 25 that may consist of warp cotton yarns 22 and filling cotton yarns 23. The fabric 25 carries a coating of adhesive material on each side as shown at 26 and 26a. Fabric of this sort may be cut into strips in accordance with my invention and one edge treated on both sides in the region of the edge portion 10a with resist as shown at 9a and 9b. In the case of a coated fabric such as that shown in Fig. 8 the coating 26 which faces the adhesive-carrying lining 15 in the completed collar may, if desired, be omitted as shown in Fig. 9 because the adhesive carried by the lining will cause the strip 10 to become fused with the lining except where the resist 9a is applied along the edge 10a when the adhesive carried by the lining is activated during the fusing of the collar plies. However, for the purpose of more readily effecting temporary adhesion of the strip 10 to the lining 15 during collar manufacture it is preferable that the strip 10 present an adhesive as a coating or otherwise on the surface to be adhered to the lining so that it can be plasticized to a certain extent, thereby facilitating the initial temporary adhesion.

It is preferred that strip 10 carry adhesive material as a coating or otherwise on the surface thereof which faces the back ply so that the strip 10 and the back ply will be fused together in the completed collar except where the resist is applied along the edge portion 10a. However, some of the advantages herein described can be obtained when the strip 10 does not carry adhesive on this surface. For example, in the case of a coated fabric such as that shown in Fig. 8, the adhesive coating 26a may be omitted as shown in Fig. 10, in which case the resist 9b would not be necessary and

could be omitted as likewise shown in Fig. 10. In the production of a collar of this type it is also the case that a strip of ordinary fabric may be employed which does not present an adhesive surface on either side, as by omitting both of the coatings 26 and 26a of Fig. 8 as shown in Fig. 11. In such case the resist 9a would be employed in the region of the edge portion 10a and the strip 10 would ultimately become fused to the adhesive-carrying lining ply except where the resist 9a is applied to the edge portion 10a of the strip 10, but in this case the backing ply would be unadhered to the strip 10. When the strip 10 has resist material applied to both surfaces thereof in the region of the edge portion 10a as shown in Figs. 7, 8 and 9 the disposition of the strip 10 in the finished collar will be that illustrated in Figs. 12 and 13. However, when the resist material is applied to the edge portion 10a on that surface only which opposes the lining ply in the finished collar, as shown in Figs. 5, 6, 10 and 11, then the disposition of the strip in the finished collar will be as illustrated in Figs. 2 and 3. In Figs. 2, 3, 12 and 13 no attempt has been made to show the adhesive for during the fusion operation the adhesive merges with the fabric plies and is not apparent in the collar as a well defined layer. While the resist material 9, 9a and 9b has been shown where it occurs in Figs. 2, 3, 12 and 13 it is to be understood that when the resist material is water soluble, as is usually the case, the resist material is removed upon the first washing of the collar after it has served its function during the fusing operation of preventing fusion in the region or regions where it is applied so that the opposing layers of fabric in these regions will remain free and unadhered with respect to each other.

While the strip 10 is permanently held in place in the finished collar by virtue of its fusion with the lining ply or with the lining ply and the back ply except along the edge portion 10a where it is unadhered, one may, if desired, reinforce the fixation of the strip 10 in the finished collar as by one or more rows of stitching 27 as shown in Figs. 2 and 3.

The strip 10 may run the entire length of the collar or may stop short of the ends as indicated in Fig. 1. Desirable effects are sometimes obtained by omitting the tape in the neighborhood of the ends of the collar. In this manner no softening is produced at the foldline in the neighborhood of the ends, thereby creating a roll effect.

A convenient resist material to use is a water soluble cellulose ether, which creates a thin strong film which prevents fusion and which is eliminated on the first washing. It is to be understood that it is only after the elimination of resist by washing that the real softening effect is obtained.

The strip 10 must be placed with the edge 10a thereof positioned with respect to the contours of the collar. In order to achieve this result I have developed special manufacturing techniques which are disclosed in my aforesaid application Serial No. 79,758. According to this technique the strip 10 is preferably plasticized so that it may be temporarily adhered to the lining 15 in the process of manufacture by the mere application of heat and pressure without resorting to the use of solvents. Subsequent permanent fusion of the strip 10 to the lining 15 and also to the back ply 16 is achieved when the collar is fused as a whole in the final fusing

operation, as described in my Patents 1,968,409-10. The resist 9 or 9a-9b is preferably applied after the plasticizing operation.

The foregoing constitutes the preferred practice of one form of this invention. However, if the resist 9 of the tape shown in Figs. 5 and 6 or if the resist 9a or 9b of the strips shown in Figs. 7, 8 and 9 were to be omitted, some discontinuity of stiffness at the collar foldline results, but the definition of the foldline is not nearly as satisfactory as in the case of the preferred practice of this invention as described and illustrated hereinabove.

The embodiment of my invention which has been described above in connection with Figs. 1 to 13 inclusive is substantially the same as that described in my above-mentioned now abandoned application Serial No. 79,757 of which this application is a continuation-in-part. All the embodiments shown in Figs. 1 to 13 inclusive make use of a resist to create a softening effect along the foldline of the collar. However, a softening effect also can be obtained without using any resist, as described hereinbelow and as disclosed in my above-mentioned application Serial No. 153,050 of which this application likewise is a continuation-in-part, by using a flexible weave in the edge portion 10a of the strip 10 which falls in the zone 10z. If a thin tissue, e. g. a thin flexible weave is adhered to the lining ply along the zone 10z, then this zone is rendered more flexible than the stiffened collarband and, provided that said tissue or weave is substantially more flexible than the fabric of the back ply of the collar, the said zone also will be more flexible than the portion of the collartop adjacent thereto. Figs. 14 and 15 show a tape in which no resist is employed, but in which the foldline-forming zone of the tape is obtained by means of a flexible weave.

The tape shown in Figs. 14 and 15 comprises essentially two portions, namely, a stiffening portion indicated by S and a softening portion indicated by T. The stiffening portion S comprises a sequence of cellulose derivative warp yarns A, and a sequence of cotton warp yarns C, with two of the warp yarns C separating each pair of warp yarns A. (This warp yarn structure is customary in interwoven adhesive-bearing collar linings and is similar in this respect to the showing in Figs. 4 to 7.) The warp structure of the softening portion T contains no latently adhesive yarns; and it may consist entirely of cotton yarns which are either substantially lighter than the cotton yarns of the stiffening portion, or it may consist of cotton yarns which are more widely separated than the yarns C of the stiffening portion, or preferably it may, as shown, consist of cotton yarns which are both lighter and more widely spaced. Still more preferably, the warp yarns of the softening portion T may be made of rayon, e. g. Bemberg or viscose, say 100 denier, which are both light and flexible and which are inherently more flexible than the warp yarns in the body portion of the tape. Moreover, such inherently more flexible warp yarns may be more widely spaced from one another as compared with the warp yarns of the stiffening portion. For example, the warp count in the stiffening portion (cotton and acetate) may be 100 ends per inch, whereas the warp count in the softening portion may be 50 ends per inch of 100 denier Bemberg. At the junction between the stiffening and softening portions, I prefer to have two adjacent cellulose derivative yarns

as shown at A₂ in Fig. 15. The overall width of the stiffening portion S, including the extra pair of acetate yarns A₂ may be $\frac{1}{4}$ " or $\frac{1}{8}$ "; while the overall width of the softening portion T may be $\frac{1}{8}$ " or $\frac{1}{16}$ ". It will be understood that these dimensions are merely indicative of good practice and constitute no limitation.

The weft, schematically indicated at W in Fig. 14, is conventional and may consist, for example, of No. 30's cotton, more or less. A tape constructed in this way provides the stiffening of the band portion and the relative softening of the foldline portion, provided that the fabric of the collar itself is of normal construction, for example, the conventional shirting broadcloth counting, for example, 136 x 60. It will be understood that when a tape of the kind shown in Figs. 14 and 15 is used, the softening portion S adheres to the lining as shown in Fig. 16. Moreover, it will be understood that when the softening portion becomes fused with the lining ply as shown in Fig. 16 it exerts a softening effect as compared with the collartop portion of the collar only by virtue of the fact that it is substantially lighter and/or more flexible than the fabric of the back ply of the collar, although in any case discontinuity of collar stiffness is provided between the stiffening portion T and the softening portion S.

It will be understood that I may combine the expedients of using resist and of using a flexible tissue as an integral portion of the tape. There is in fact an advantage in doing just this, because the flexibility of the weave in the softening zone of the tape of Figs. 14 and 15 makes the tape somewhat difficult to handle in the manufacturing processes of the collar. Treating this light, flexible weave with a very light starch or other material, e. g. a water-soluble cellulose ether, will stiffen this portion sufficiently for convenient handling in the manufacturing operation and at the same time will cause no untoward effects, because this material will be eliminated in washing. When a resist is employed by applying it to the softening portion T of the tape shown in Figs. 14 and 15 the tape will be as shown in Fig. 17 which is identical with Fig. 15 except for the presence of the resist 9 along the edge portion 10a that constitutes the softening portion T and the finished fused collar will be as shown in Figs. 2 and 3, rather than Fig. 16, and will have the advantages hereinabove described in connection with Figs. 2 and 3 plus the further advantage of a still greater softening effect being obtained along the collar foldline because of the fact that the fabric of the tape in the marginal zone that is disposed along the collar foldline is of substantially more flexible construction as compared with the fabric in the body portion of the tape that is disposed in the collarband. However, whether either expedient is employed, namely, the use of resist along and adjacent the margin of the tape that extends into the foldline or the use of more flexible fabric construction in this zone, and likewise when both expedients are employed, the tape provides a unitary structure having the dual function above noted in that it exercises a stiffening effect in the region of the collarband portion of the collar and exerts a softening effect along the collar foldline. In this connection the effect of the fusing operation on a collar is to stiffen it, and by the expression "softening effect" as used in the specification and claims, I mean essentially the effect of imparting less stiffness than

that of adjacent portions of the collar. Where resist is used it will be understood that the softening effect thus defined is not necessarily achieved until after the resist is removed by washing.

While the embodiment of this invention wherein a tape-like strip is preformed so as to have a marginal portion which is of more flexible fabric construction as compared with the fabric construction of the body portion of the strip has been exemplified in connection with a strip presenting latent activatable adhesive in the form of yarns that are woven into the body portion of the strip as shown in Figs. 14 and 15, it is apparent that corresponding differences in the flexibility of the fabric construction likewise can be availed of according to this invention when the latent activatable adhesive, instead of being woven into the fabric in the form of yarns, is carried in the form of a coating as described hereinabove in connection with Figs. 8 to 10.

I claim:

1. A one-piece fused collar having a collartop portion and a collarband portion and comprising at least two plies fused together in face to face relation substantially throughout and a strip of fabric in the collarband portion of the collar, one surface of which is fused to one of said plies except for a narrow zone adjacent the one edge of said strip that is disposed in the collar foldline and the opposite surface of which is fused to a third ply except in said narrow zone adjacent said edge of said strip, said third ply and the ply on the opposite side of said strip being fused together in face-to-face relation substantially through except where said strip is interposed therebetween, thereby providing at least two plies fused together in the region of the foldline which impart substantial stiffness in said region, two additional plies of fabric fused therewith and to each other in the collarband portion of the collar which impart substantially increased stiffness in the region of said collarband portion immediately adjacent said foldline and one additional ply of fabric fused therewith in the collartop portion of the collar which imparts greater stiffness than that in said foldline region, the discontinuity in stiffness between said foldline region and the bordering collarband and collartop portions of the collar being produced by said strip and being located by the border between said unadhered zone of said strip which is disposed in the collar foldline and the portion of said strip in the collarband which is fused to the collar plies in contact with the surfaces thereof.

2. A one-piece fused collar having a collartop portion and a collarband portion and comprising a plurality of fabric plies, said collar comprising a foldline-forming strip of fabric disposed between two of said plies, said strip of fabric having an elongated body portion which is located in said collarband portion of the collar and having a marginal zone of narrow but substantial width extending into and disposed along the foldline between the collarband and collartop portions of the collar, at least one of the surfaces of said strip of fabric being fused to a collar ply in contact therewith except in the region of said zone leaving said region of said surface free and unadhered with respect to said ply, and said two plies being fused together substantially throughout except where said strip of fabric is interposed therebetween.

3. A one-piece fused collar according to claim 2 wherein said collar comprises a face ply, a

lining ply and a back ply, wherein said strip of fabric is interposed between said lining ply and said back ply, and wherein said lining ply presents adhesive material on the opposite surfaces thereof to which said face ply and said back ply are fused substantially throughout except where said strip is interposed between said lining ply and said back ply.

4. A one-piece fused collar according to claim 2 wherein the opposite surface of said strip in the region of said zone is free and unadhered with respect to the other of said two plies.

5. A one-piece fused collar according to claim 2 wherein the fabric of said strip in the region of said zone is composed of fabric having substantially greater inherent flexibility as compared with the fabric of said strip in the region of said body portion.

6. A one-piece fused collar having a collartop portion and a collarband portion and comprising a plurality of plies and a strip of fabric which is interposed between two of said plies and which has an elongated body portion disposed in and along the collarband portion of the collar and an elongated zone of narrow but substantial width adjacent one edge of said strip and extending into and disposed along the foldline between the collartop and collarband portions of the collar, said two plies being fused together substantially throughout except where said strip is interposed therebetween and said strip being fused to each of said two plies except on at least one surface thereof in the region of said zone leaving said surface of said strip in said region of said zone free and unadhered with respect to the ply in contact therewith thereby providing in said collar a stiffened zone where said body portion of said strip is fused to the plies in contact therewith in the collarband portion of the collar and an adjacent narrow, elongated, more flexible zone along and defining the foldline between the collarband and collartop portions of the collar where said zone of said strip is free and unadhered with respect to at least one of the plies in contact therewith.

7. A one-piece fused collar having a collartop portion and a collarband portion and comprising a plurality of plies and a tape-like strip of fabric interposed between two of said plies, said two plies being fused together in face-to-face relation substantially throughout except where said tape-like strip of fabric is interposed therebetween, said tape-like strip of fabric having an elongated body portion disposed in and along the collarband portion of the collar and a bordering elongated zone of narrow but substantial width adjacent one edge of said strip and extending into and disposed along the foldline between the collartop and collarband portions of the collar, said strip of fabric being fused to each of said two plies except in the region of said zone, thereby providing in said collar a stiffened zone where said body portion of said strip is fused to the plies in contact therewith in the collarband portion of the collar and an adjacent narrow, elongated, more flexible zone along and defining the foldline between the collarband and collartop portions of the collar where said zone of said strip is free and unadhered with respect to the said plies in contact therewith.

8. A one-piece fused collar having a collartop portion and a collarband portion and comprising a plurality of plies and a tape-like strip of fabric interposed between two of said plies, said two

plies being fused together substantially throughout except where said tape-like strip of fabric is interposed therebetween, said tape-like strip of fabric having an elongated body portion disposed in and along the collarband portion of the collar and a bordering elongated zone of narrow but substantial width adjacent one edge of said strip and extending into and disposed along the fold-line between the collartop and collarband portions of the collar, the fabric of said strip in the region of said zone being of substantially more flexible construction as compared with the fabric of said strip in the region of said body portion, said strip being fused to each of said two plies except on at least one surface thereof in the region of said zone leaving said surface of said strip in said region of said zone free and unadhered with respect to the ply in contact therewith.

9. A one-piece fused collar according to claim 8 wherein the more flexible construction of the fabric of said strip in the region of said zone comprises greater spacing of the warp yarns in the region of said zone as compared with the spacing of the warp yarns in the body portion of said strip.

10. A one-piece fused collar according to claim 8 wherein the more flexible construction of the fabric of said strip in the region of said zone comprises warp yarns of lesser diameter as compared with the diameter of the warp yarns in the body portion of said strip.

11. A one-piece fused collar according to claim 8 wherein the more flexible construction of the fabric of said strip in the region of said zone comprises warp yarns composed of material having greater inherent flexibility as compared with the material of the warp yarns in the body portion of the strip.

12. A one-piece fused collar according to claim 8 wherein the fabric of said strip in the region of said zone is of substantially more flexible construction as compared with the fabric of at least one of said two plies.

13. A one-piece fused collar according to claim 8 wherein said collar comprises a face ply, a lining ply and a back ply, wherein said strip of fabric is interposed between said lining ply and said back ply, wherein said lining ply presents adhesive material on the opposite surfaces thereof to which said face ply and said back ply are fused substantially throughout except where said strip is interposed between said lining ply and said back ply, and wherein the fabric of said strip in the region of said zone is of substantially more flexible construction as compared with the fabric of said back ply.

14. A one-piece fused collar according to claim 8 wherein said strip of fabric in the region of said zone is free and unadhered with respect to each of said two plies.

15. As an article of manufacture a preformed

fold-line-forming fabric strip having a longitudinally disposed body portion and a zone of narrow but substantial width along and adjacent a margin thereof, said strip of fabric when disposed in contact with an adhesive-carrying fabric being adapted to become fused therewith at least in the region of said body portion to stiffen said fabric in said region and, as so fused, to provide discontinuity of stiffness along the edge of said region between said body portion and said zone.

16. As an article of manufacture, a preformed fold-line-forming strip of fabric having a longitudinally extending body portion and a zone of narrow but substantial width along and adjacent a longitudinal margin thereof which is of substantially more flexible construction as compared with the fabric of said strip in the region of said body portion.

17. As an article of manufacture, a preformed fold-line-forming strip of fabric according to claim 16 wherein at least one surface of said strip of fabric presents exposed latent activatable adhesive only in the region of said body portion thereof.

18. As an article of manufacture, a preformed fold-line-forming strip of fabric according to claim 16 wherein one surface of said strip carries resist material only in the region of said zone.

19. As an article of manufacture, a preformed fold-line-forming strip of fabric having a longitudinally disposed body portion and a zone of narrow but substantial width along and adjacent a longitudinal margin thereof, at least one surface of said strip of fabric presenting exposed latent activatable adhesive only in the region of said body portion.

20. As an article of manufacture, a preformed fold-line-forming strip of fabric according to claim 19 wherein the opposite surface of said strip of fabric carries resist material only in the region of said zone.

21. As an article of manufacture, a preformed fabric strip having a longitudinally disposed body portion and a zone of narrow but substantial width along and adjacent a longitudinal margin thereof, said strip carrying resist material on at least one surface of said strip and said resist material being carried by said strip only in the region of said zone.
